UNITED STATES PATENT OFFICE.

JAMES A. HERRICK AND CHARLES R. F. TOPHAM, OF BROOKLYN, N. Y.,
ASSIGNORS TO HENRY ARTHUR GADSDEN, OF LONDON, ENGLAND.

GAS-PRODUCER.

SPECIFICATION forming part of Letters Patent No. 360,222, dated March 29, 1887.

Application filed January 22, 1886. Serial No. 189,382. (No model.)

To all whom it may concern:

Be it known that we, JAMES A. HERRICK and CHARLES R. F. TOPHAM, both citizens of the United States, residing in Brooklyn, New York, have invented certain Improvements in Gas-Producers, of which the following is a specification.

One of the main objects of our invention is to so construct a gas producer or generator as to provide for the even distribution of the coal in feeding, to obtain a uniform and thorough combustion, and to protect the feed-hopper.

Further features of our invention relate to the construction of the hopper, the flues, the tuyeres, and the door-frame, and other details, as fully described hereinafter.

In the accompanying drawings, Figure 1 is a vertical section of a producer embodying our improvements, the section being taken on the line J K, Figs. 2 and 3. Fig. 2 is a vertical section on the line H I, Fig. 1. Fig. 3 is a front view with part of the central tuyere and throat broken away and with the right-hand door to the ash-pit removed. Fig. 4 is a sectional plan view on the line C D, Fig. 1. Fig. 5 is plan view, partly in section, on the line A B, Fig. 2. Fig. 6 is a sectional view (drawn to an enlarged scale on the line O P, Fig. 7) of a modification; and Fig. 7 is a sectional plan 30 of the same on the line M N, Fig. 6.

We have illustrated our gas-producer as of rectangular form in sectional plan; but it should be understood that it may be of any convenient shape. We have also represented the downtake flue E as built in with the structure of the producer; but it may be separate therefrom without departure from our invention. We prefer, however, to make the structure in the rectangular form shown and 40 with the downtake flue built in therewith, for several reasons. A number of producers can in such case be built in continuous range in pairs, with the downtake flues between each two producers, as indicated at E e, Fig. 5, 45 where the dotted lines to the right indicate a portion of the adjacent producer. If desired, the producers may be put up in blocks of four, the rear wall and one side wall being common to two adjoining producers, and the offtakes

of all four producers may communicate at one corner with a common offtake at the center of the structure; or, if preferred, only the back walls may be in common and the downtakes in line, as shown in Fig. 5, and all deliver into one common flue below, Fig. 2.

In some cases, where only one producer is used, it may be provided with two downtakes, as indicated at E e in Fig. 4, with ordinary bindings, G. If only one downtake is provided, as in Fig. 5, the space for the second one may be filled in with earth or loose rubble. This we prefer to attaching an outside flue to the structure, on account of the difficulty of binding the same securely against the expansion and contraction caused by the heat.

Referring to the drawings, 1, 2, 3, and 4 are the front, rear, and side walls, respectively, of the producer, and 5 is the top or roof, which is provided with a central feed-hopper, 6, and counterbalanced bell 7. The preferred detailed construction of these parts will be referred to hereinafter.

One of the main features of our invention consists in providing the producer with a central arch or diaphragm, 8, at the upper part 75 of the combustion chamber L, preferably at such a distance below the bottom of the feed-hopper that when the bell 7 is depressed the latter will rest on the top of the arch, as shown by dotted lines in Fig. 2. This arch is for the 80 purpose of providing for an even distribution of the coal fed into the combustion-chamber, of protecting the bell and hopper, and of increasing the uniformity of the combustion as a resort for mixing and heating the gases previous 85 to their exit. This arch or diaphragm is provided at its juncture with the walls of the structure with openings 9, which we arrange at the four sides, as illustrated in Fig. 5, and thereby obtain an equalized distribution and 90 combustion of the fuel. The arch 8 is built at the corners with inclined ridges 10, in order to facilitate the descent of the coal (when the bell 7 is depressed) through the openings 9 into the combustion-chamber L. By this 95 means the coal falls on all sides evenly, instead of in a mass in the center, as is usual.

The construction of an arch or diaphragm,

above described, may be used in connection with any suitable form of offtake, hopper, and roof; but we prefer the construction of hopper and roof illustrated in the drawings.

- 5 The roof 5 is built up of brick-lined plates or frames, which are provided with suitable poke-holes, 12, and at the corners are detachable lined covers 13, to fit corresponding flanged openings in the top plates. The covers are 10 provided with handles 13' for lifting them, in order that access may be had to the interior of the producer for repairs whenever necessary, and for starting preliminary fires, and for feeding the same temporarily. This construction of brick-lined frame, resting on the masonry and provided with lined removable covers carrying the hopper, is to be distinguished 15 from the ordinary sheathing which incases the masonry.
- 20 We are aware that movable lined frames have been used for the tops of furnaces, but believe it to be new to construct such a frame with a bell and hopper, as described.

The hopper 6 is constructed of four flanged 25 plates, forming the four sides of the rectangular hopper, bolted together and also bolted to the ring 14 on the roof of the producer, which ring has its interior diameter round, as shown by dotted lines in Fig. 5, to correspond with 30 the round outline of the bell 7, which finds its seat against this ring, as illustrated in Figs. 1 and 2. The top of the hopper may be provided with the usual slide, 15.

We are aware that hoppers have been provided 35 with detachable rings at their lower ends; but we are not aware that such detachable rings have been bolted between the flanged bolted plates constituting the hopper and the top of the producer so that the bell will find 40 its seat against this ring and be pressed up tightly against it by its counterbalance.

The downtime flue E may be provided with various forms of valve; but we prefer the valve 45 16, illustrated in Fig. 1. The stem of the valve, which passes up through the cover-plate 17, is provided with a handle, 18, and a hinged latch, 19. This hinged latch, when the valve is depressed, as illustrated in Fig. 2, occupies the position shown by full lines in that 50 figure; but when the valve is raised off its seat the latch 19 will assume a vertical position and keep the valve raised; but by simply kicking this latch aside with the foot the workman can allow the valve to drop and close 55 the downtime flue instantly.

The poke-holes 12 in the top of the producer are in such positions that the walls of the combustion-chamber L are readily accessible therefrom to keep the walls clear of soot and clink- 60 ers. Soot-holes 11, also, may be arranged in the walls of the producer above the arch, to facilitate the removal of soot deposits, should these occur.

For ordinary coking coals we prefer to construct our producer with grate-bars 20, as 65 illustrated in Figs. 1 and 2, extending entirely across the lower part of the producer and sup-

ported on front bearer-bars, 21, and a rear bearer-bar, 22. Each front bearer-bar is mounted at one end in a lug in the side wall, 70 and at the other end in a lug, 24, cast on the central tuyere-box, F, Figs. 1, 6, and 7, while the rear bearer-bar, 22, reaches entirely across the ash-pit, and is supported in lugs or sockets 75 23 on the side walls, Fig. 1. For non-coking coals or dust, and for slack, special grates of various forms may be used in connection with the main features of our producer without departure from our invention.

The central tuyere-box, F, is carried by the 80 door-frame 25, and may be formed in two parts, as illustrated in Fig. 4, the outer part, 26, being stemmed into and bolted to the inner part, 27, which latter is formed in one structure with the door 25. If preferred, the inner part, 27, 85 of the tuyere-box, as well as the outer part, 26, may be stemmed into the portion 27' of the door-frame, as shown in Figs. 6 and 7.

The inner end of the tuyere-box is flared outwardly, as illustrated in Figs. 4 and 7, to 90 facilitate the distribution of the air and steam blast to all parts of the ash-pit, and, if desired, the top and sides of the tuyere-box immediately under the grate-bars may be perforated, as indicated by dotted lines in Fig. 4 95 and in full lines in Figs. 6 and 7, to allow of currents of air passing up between the bars to that point.

The inner end of the tuyere-box is provided with a lip, 28, as indicated by dotted lines in 100 Fig. 1 and by full lines in Figs. 4 and 6, and the outer end is provided with a lip, 29, which, in connection with the front plate, 30, forms a trap, so that water collecting thereon from the steam from the blast will close the opening at 105 that point. The door-frames, tuyere-box, and poke-hole boxes, hereinafter referred to, may, however, be cast in one structure, if desired.

On the top of the outer portion, 26, of the tuyere-box is mounted any usual form of throat, 110 31, which, for a purpose explained hereinafter, is hinged at 32 to the top of the box, and at 33, at its upper end, to a stanchion projecting from the wall of the structure, so that it can be swung back from the position indicated by 115 full lines in Figs. 4 and 5 to that indicated by dotted lines in Fig. 4. The top of the throat may be closed by the usual hinged cover, 34. The bottom of the throat is set into the lipped top 44 of the tuyere-box, Fig. 6, and is provided with a packing of sand, clay, &c., to insure a tight joint. The throat is provided with lugs 59, to facilitate the manipulation of the throat by the insertion of a bar, 60, Figs. 1 and 6, under the lugs. By resting the end of 125 the bar on the door-frame as a fulcrum point, the throat may be lifted clear of the box and swung back, and the throat may be returned to its normal position in a similar way.

On each side of the door-frame, and preferably above it, are mounted in notches in the front wall of the producer smaller throats, 35, which open into flues 36, extending horizontally around the combustion-chamber in the

walls of the producer, but not communicating with each other, as indicated by dotted lines in Fig. 2, and each flue 36 is provided with outlets 37, opening into the incandescent body 5 of coal in the combustion-chamber. In connection with these throats 31 and 35, we provide a suitable system of steam pipes and nozzles, 38, controlled by valves or cocks in any suitable manner. The main pipe of this system is provided at its lower end with a drip-pipe, 39, controlled by a cock, 40, and having at its lower end a nozzle, 41, adapted to fit into a valved opening, 42, in the cover-plate 30 of the tuyere-box F, so that when the nozzle 41 is turned to open into the tuyere-box and the valve 40 is opened the water of condensation in the pipe may be thrown into the tuyere-box, instead of being allowed to drip on the ground outside and be a source of annoyance. Live steam may also be blown in, if desired, by the same means.

The extension 39 is connected to the main pipe 38 by a hinged joint, 61, so that when it is desired to move it out of the way the extension 39 may be lifted to the horizontal position indicated by dotted lines in Fig. 3, and its outer end supported by a hook, 43, projecting from the front wall of the structure.

The doors 45 on each side of the central tuyere-box are hinged to the door-frame in any suitable manner, and when closed are secured tight by bars 46, Figs. 3 and 6, fitting at one end in lugs in the door-frame and at the other end in lugs on the top of the tuyere-box, while the inner face of the bar bears against wedge-pieces 47, cast on the front of the doors. The lower part of each door is held to the frame by a bar, 48, common to both, and fitting in lugs on the door-frame, Figs. 3 and 40 7. A niche in the wall allows the doors to swing back flush with the face of the structure.

Each door is provided above and below the grate-level with suitable poke-holes, 49, with hinged covers, and in the door-frame are 45 mounted lazy-bars 50, to receive the weight of the slicing bar or poker introduced to remove the ashes.

Near the upper part of the door-frame, at opposite sides, are lugs 51, which receive and 50 support a detachable cross-beam, 52, for the support of false grate-bars 53, indicated by dotted lines in Fig. 1, and which are supported at their inner ends on a ledge, 55, of the rear wall, 2. These false bars 53 are inserted when 55 it is desired to perfectly clean out the clinkers and ashes or the lower part of the fire. To facilitate the forcible introduction of the bars, a ram, 54, is provided, suspended from a traveling hook, 56, mounted on a way, 57, secured to the front wall of the producer. With ordinarily clean coal, however, it is not necessary to use false bars, except for occasional thorough cleanings.

We are aware that in charging retorts ways 65 with traveling hooks have been provided to support the charging-shovel; but our con-

struction of a single traveling way running across the face of the retort with a suspended chain and bar would be inapplicable for retort-charging.

In the front wall, 1, and side walls, 3, are poke-boxes 58, for the introduction of bars to handle the fuel in the combustion-chamber L, as well as to remove clinkers from the walls. We prefer to arrange the poke-holes in the 75 side wall, 3, at points above or higher up than those in the front wall, 1. The poke-boxes 58 in the front wall are mounted on the door-frame 25, but built in the masonry, and are separate from the door-frame. 80

We claim as our invention—

1. The combination of the combustion-chamber of a gas-producer and offtake-flue with a diaphragm or arch in the combustion-chamber having openings at its edges and 85 inclined ribs between the openings.

2. A gas-producer having walls of masonry and having a roof formed of a lined metallic frame supported on but independent of the masonry and provided with a bell and hopper 90 and with detachable lined covers.

3. The combination of the top of the gas-producer with a bell and rectangular hopper formed of flanged plates bolted together and to the producer, and a ring, 14, bolted between 95 the top of the producer and the hopper to form a seat for the bell, all substantially as specified.

4. The combination of the grate-bars of a gas-producer and a central tuyere-box parallel with the bars, transverse supporting-bars 21 and 22, and lugs for the supporting-bars on the side walls and on the tuyere-box. 100

5. A gas-producer having a tuyere-box provided with a front plate and outer lip, 29, to 105 form with the front plate a trap, substantially as and for the purpose set forth.

6. The combination of the tuyere-box of a gas-producer having an opening, 42, with a throat and steam-pipes having an extension, 39, adapted to direct the drip into the tuyere-box. 110

7. The combination of the throat and tuyere-box of a gas-producer with the steam-pipes therefor having a hinged drip-extension, 39, and supporting-hook 43. 115

8. The combination of the tuyere-box and door-frame of a gas-producer with a hinged throat having lugs on its sides, as and for the purpose described. 120

9. The combination of the grate of a gas-producer, a tuyere-box below the same, and a throat for the tuyere-box, with side flues, 36, and throats 35 therefor, and piping 38 for the several throats, substantially as described. 125

10. A gas-producer having side flues, 36, and throats 35 therefor in niches in the side walls.

11. The combination of the door-frame and doors of a gas-producer having poke-holes 130 and lazy-bars 50, as set forth.

12. The combination of the double door-

frame of a gas-producer with a tuyere-box, F, fixed in the said frame between the two doors, substantially as set forth.

13. The combination of the door-frame of a gas-producer with poke-holes 58, built in the masonry and mounted directly upon the door-frame, but separate therefrom.

14. The combination of a gas-producer with a way, 15, across the front thereof, and a traveling hook, 56, suspended at the front and carrying a chain and bar, 54, to facilitate the pushing in of false bars, substantially as set forth.

15. A tuyere-box for a gas-producer having a flared end and perforated top and sides, substantially as set forth.

In testimony whereof we have signed our names to this specification in the presence of two subscribing witnesses.
